SHOEMAKING METHOD AND MEANS
THEREFOR

Max Garfinkel, Joseph Ruiz, and William L. Duga, San Francisco, Calif., assignors to The Del-Mac Shoe Process Corporation, New York, N. Y.

Application March 12, 1934, Serial No. 715,216
Renewed November 5, 1936

2 Claims. (Cl. 12—103)

This invention relates to improvements in complementary insole-outsole combinations and to an improved method of producing the same, whereby accurate assembly of the insole and outsole so that they exactly interfit will not be necessary to insure comfort to the user of a shoe employing the combination, and whereby the combination may be easily and expeditiously produced by a single splitting operation making use of a splitting machine such as is commonly employed at shoe factories.

In the production of complementary insole-outsole combinations for shoes, it has been heretofore proposed to split the heel and shank portions of a leather sole blank to form insole and outsole shank pieces, then remove a rand from the margin of the ball section of the sole blank at the flesh side of the latter by separate channel cutting operations which leave the rand attached to the forward end of the insole shank piece, and to then separately cut inwardly from the flesh side of the sole blank on a transverse line extending from terminal to terminal of the rand so that the insole blank is severed from the outer sole, a projection being formed on the ball section of the outer sole, and an opening being formed in the ball section of the inner sole in which said projection will snugly fit. Combinations produced by this old method are objectionable because the projection on the outer sole and the opening in the inner sole have relatively short abruptly inclined marginal edges, and if they are not exactly meshed or interfitted when the inner sole and outer sole are assembled, ridges will be produced on the inner face of the combination that will cause discomfort to the wearer of the shoe in which the combination is incorporated. The present invention overcomes this objection by producing a combination in which the projection on the outer sole and the opening in the inner sole have relatively long gradually inclined marginal edges, the leather of the inner sole tapering to a feather edge about the opening so that no noticeable ridges will be produced on the inner surface of the combination if there is a slight inaccuracy between the meshing or interfitting of the outsole projection with the insole opening.

Further, the above described prior method of producing combinations involves at least three separate and different skillful operations consisting in splitting the sole blank from the rear end of the heel to a certain transverse line at the junction of the ball and shank sections of the blank, then providing a combination of horizontal and inclined channel cuts with the horizontal

channel cuts forming a continuation of the split so that a rand is separated from the margin of the ball section of the sole blank, and then finally forming a cut transversely from terminal to terminal of the rand so as to completely sever the insole blank from the outer sole. Besides requiring the exercise of care and skill, these three operations require the expenditure of considerable time and the use of a plurality of types of machines, suitably modified. The present invention has the advantage over this old method in that it provides a method which may be more expeditiously carried out without the exercise of great care or skill and by only a single operation performed on an ordinary splitting machine.

More particularly, the present invention contemplates the provision of a template for properly controlling the operation of the knife of a splitting machine on a sole blank so as to produce the improved insole-outsole combination in accordance with the present improved method.

Further objects of the present invention are to so construct the template that it may be readily interchangeably employed for the production of both right and left hand insole and outsole combinations, and to so construct the template that the insole will be formed with a thickened shank section which will not require a separate shank reinforcement.

With the above general objects in view, and others that will become apparent as the nature of the invention is better understood, the invention consists in the novel construction and method hereinafter more fully described, illustrated in the accompanying drawings, and claimed.

In the drawings:

Figure 1 is a top plan view of an insole-outsole combination produced in accordance with the present invention.

Figure 2 is a longitudinal section on line 2—2 of Figure 1.

Figure 3 is a transverse section on line 3—3 of Figure 1.

Figure 4 is a top plan view of the outer sole forming part of the combination shown in Figure 1.

Figure 5 is a bottom plan view of the insole forming part of the combination shown in Figure 1.

Figure 6 is a plan view of the template employed on a sole blank while running the same through a splitting machine, for producing the combination shown in Figure 1 in accordance with the present method.

Figure 7 is a longitudinal section on line 7—7 of Figure 6.

Figure 8 is a transverse section on line 8—8 of Figure 6.

Figure 9 is a sectional view showing an insole and outsole combination in process of production by the means and method forming part of the present invention.

Figure 10 is a view similar to Figure 9 with the combination progressed further on in the process of its production; and

Figure 11 is a fragmentary transverse section of the parts in the position of Figure 9, showing how the margin of the ball section of the sole blank is depressed by the corresponding portion of the template into the path of the knife of the splitting machine so that said knife will remove a rand from the margin of said ball section as the sole blank and template are fed between the rollers of the splitting machine.

Referring more in detail to the drawings, 10 indicates a sole blank having flesh and grain sides indicated respectively at 11 and 12. In the production of the combination, a template 13 is placed 25 upon the grain side of this blank and passed with the latter through an ordinary splitting machine as generally illustrated in Figures 9 to 11 inclusive. The template 13 is made of fiber or any other suitable relatively stiff and unyielding material, so as to substantially conform in outline to the outline of the sole blank 10 and to provide a ball portion or section 14 provided with a central opening 15, a shank portion 16, and a heel portion 17. The ball portion 14 is gradually tapered in thickness for a considerable distance, preferably similarly upon opposite sides as at 18, inwardly to the opening 15 and to a feather edge as at 19. Also, the shank and heel portions 16 and 17 are of increased thickness compared to the thickness of the ball portion 14, preferably by similarly increasing the thickness of these portions 16 and 17 on opposite sides of the template as indicated at 20.

As is well known in the art, an ordinary splitting machine includes a pair of superposed feed rollers 21 and 22, and a horizontal knife 23 located at the discharge side of said feed rollers and in proximity to the top of the lower roller 22, the material to be split being fed by the rollers to the knife.

In carrying out the present method, the template 13 is registered with and laid upon the grain side of the sole blank 10, whereupon the registered template and sole blank are fed between 55 the rollers 21 and 22 of the splitting machine, either the ball or heel portions of the template and sole blank being first introduced between the rollers 21 and 22. We have shown the template and sole blank arranged with the ball portions 60 thereof first fed between the rollers, and it will be noted that the margin of the ball portion of the blank 10 will be held down in the path of knife 23 by the margin of the ball portion 14 of the template so that a rand 24 is separated 65 from the margin of the ball section of the sole blank at the flesh side thereof, the central part of the ball portion of the sole blank being pressed upwardly by the lower roller 22 into the opening 15 of the template and out of the path of knife 23 so as to ride over the latter. The portion of template 13 at the rear of opening 15 then forces the similar portion of the sole blank in the path of the knife 23, so that an integral connection 70 between the rear ends of the rand 24 of the same thickness as the latter is cut from the sole blank

at the flesh side of the same. The thickened shank and heel parts 16 and 17 then pass under the upper roller 21 so as to further depress the shank and heel portions of the sole blank 10, whereby these portions of the sole blank are 5 split to form insole shank and heel portions 26 and 27 respectively of increased thickness compared to the thickness of the rand and connecting portions 24 and 25, and outsole shank and heel portions 28 and 29 of reduced thickness compared 10 to the margin of the outsole ball portion 30. By thus producing thickened shank and heel portions on the insole, separate shank reinforcements for the insole will be unnecessary when the present combination is incorporated in a shoe. 15

When the rand and connecting portion 25 are cut from the sole blank, the ball portion 30 of the outer sole is formed with a central projection 31 provided with relatively long gradually inclined or beveled marginal edges as at 32. At 20 the same time, a unitary insole is produced in which the rand 24 and connecting portion 25 form an integrally beveled marginal frame at the ball portion of said insole, the inner margin of said frame about the opening 33 in the ball portion of said insole constituting relatively long gradually inclined or beveled edges for the opening 33 exactly complementary to the marginal edges 32 of the projection 31. These internally beveled edges of the insole ball portion are such 25 that the frame composed of rand 24 and connecting part 25 tapers to a feather edge 35 at the opening 33, and the latter conforms exactly in size and shape to the size and shape of projection 31 at the upper surface of the latter. 30 The present invention therefore retains the desirable features of prior combinations in that production of the same involves no waste of leather and the provision of unitary insole and outsole elements which are absolutely complementary and will interfit perfectly when assembled. However, the present invention has the further advantage in that the relatively long gradually inclined or beveled edges of opening 33 and projection 31 will permit the insole and 40 outsole to be assembled slightly out of exact registration without producing objectionable ridges on the upper surface of the combination such as will cause discomfort to the wearer of a shoe in which the combination is incorporated. 45 This avoids the necessity of extreme care and skill in the construction of a shoe in which the present combination is incorporated, and is therefore a decided advantage over prior combinations in which the marginal edges of the 55 opening and projection in the inner sole and on the outer sole respectively are relatively short and abruptly inclined or beveled through the provision of connected horizontal and inclined channel cuts in the sole blank. 60

From the foregoing description, it will be apparent that the present invention provides for the production of a greatly improved combination of the kind in question. It will further be apparent that the invention provides for the production of this improved combination in an easy and expeditious manner and in a single operation which does not require the exercise of great skill or care and which incurs only use of a single machine such as is commonly employed 70 for splitting leather in the shoe making art.

While the template 13 is shown beveled at 18 on both sides and thickened on both sides as at 20 so that the template may be interchangeably employed in the production of both right and 75

left hand combinations, it will nevertheless be understood that the template may be beveled at 18 on only one side and enlarged at 20 on only one side, in which case separate templates 5 will be required respectively for use in the production of right and left hand combinations. Minor changes and variations in the construction and method specifically illustrated and described are contemplated within the spirit and 10 scope of the invention as claimed.

What we claim as new is:

1. The method of producing complementary insole-outsole combinations comprising the steps of providing a leather sole blank of the desired thickness of the outsole and having a grain and 15 a flesh side, placing on the grain side of said sole blank a template substantially conforming in outline to the outline of the sole blank and having its ball portion provided with a central 20 opening and its shank and heel portions of increased thickness with respect to the thickness of said ball portion, and running the superposed

sole blank and template through a splitting machine to cut a unitary insole from the flesh side of said sole blank having its lower surface exactly complementary to the upper surface of the outsole from which it is removed, with the shank 5 and heel portions of the insole of increased thickness with respect to the ball portion thereof.

2. A template for use in connection with a splitting machine in the manufacture of complementary insole-outsole combinations from 10 sole blanks, comprising a strip of fiber or like material substantially conforming in outline to the outline of the sole blank and including ball and shank portions, said ball portion having a central opening and being gradually tapered 15 thinner inwardly entirely about and to a feather edge at said opening, said shank portion being of increased thickness with respect to the thickness of the ball portion of the template.
